UNITED STATES PATENT OFFICE.

OTTO PETERMANN, OF GROTON, NEW YORK, ASSIGNOR, BY MESNE ASSIGNMENTS,
TO CORONA TYPEWRITER COMPANY, INCORPORATED, A CORPORATION OF NEW
YORK.

TYPE-WRITING MACHINE.

1,113,576.

Specification of Letters Patent. Patented Oct. 13, 1914.

Original application filed July 7, 1909, Serial No. 506,442. Divided and this application filed March 7, 1911. Serial No. 612,800.

To all whom it may concern:

Be it known that I, OTTO PETERMANN, a citizen of the Republic of Switzerland, and a resident of Groton, county of Tompkins, 5 and State of New York, have invented certain new and useful Improvements in Type-Writing Machines, of which the following is a full, clear, and exact description.

This invention relates more particularly 10 to back-spacing mechanism for front strike or visible typewriting machines, and is a division of my pending application, Sr. No. 506,442, filed July 7, 1909.

One object of the invention is to provide 15 simple and efficient means by which the carriage and platen may be moved backward a space at a time and the said mechanism so supported that the carriage, platen and back-spacing mechanism may be folded over 20 the key-levers or type-bars or otherwise moved into compact relation to another part of the machine, in order that the machine may be readily transported.

Another object of the invention is to provide 25 simple and efficient means which may be supported and held to the carriage bed in such a way that it may operate in a direction opposite to the letter spacing movement of the carriage, and which mechanism has 30 an operative element within convenient reach of the operator by which the back-spacing of the carriage may be readily accomplished.

A further object of the invention is to 35 provide a mechanism which is simple in construction and which is adapted for use in connection with various forms of typewriting machines.

With these and other objects in view, the 40 invention will be hereinafter more particularly described with reference to the accompanying drawings, which form a part of this specification, and will then be pointed out in the claims at the end of the description.

In the drawings, Figure 1 is a side elevation of one form of machine embodying my 45 invention. Fig. 2 is a fragmentary plan view, partly broken away, showing a part of the carriage bed with the back-spacing 50 mechanism applied thereto. Fig. 3 is a vertical section, partly in elevation, showing how the carriage may be propelled in one direction, and one form of escapement mechanism that may be used in connection

with the carriage for letter spacing; and 55 Fig. 4 is a fragmentary plan view showing the connection between the spring drum and the carriage for moving the same along the carriage bed.

The machine frame 10 has a support 11 60 which may be moved vertically thereon, and on said support is a bed 12 along which a carriage 13 is adapted to move. This carriage is provided with a platen 14 on each end of which is a knob 15 for manually rotating the same, and on the carriage may be arranged suitable line-spacing mechanism for the platen. The carriage may be forced along the bed in one direction by propelling mechanism of any desired construction. As 70 shown, this propelling mechanism may comprise a spring-operated drum 16 about which is a cord or other flexible connection 17, one end of which cord is passed around a pulley 18 and secured to the carriage so that the 75 tension of a spring within the drum 16 may operate to pull or force the carriage along the bed in one direction.

A rack 19 is held to the carriage and this rack is engaged by a pinion 20 forming a 80 part of an escapement mechanism. This pinion is adapted to move with a member 21 of a clutch which is adapted to engage a second clutch member 22, the latter being held to move with a shaft 23. On the shaft 85 23 and held thereto is a ratchet wheel 24 which is adapted to be engaged by suitable escapement dogs adapted to be operated by a lever or device 25, and this device 25 has one part thereof in the path of a vertically 90 movable rod or bar 26. The rod or bar 26 is adapted to be moved vertically as each key-lever 27 is depressed and said bar may be also moved by the usual space bar and with the shift levers to adapt each type-bar to 95 have a plurality of characters, and to permit the carriage to move the distance of one space each time a key-lever is depressed as is usual in typewriting machines.

The machine may be also provided with 100 suitable ribbon mechanism, and the support 11 may comprise two foldable parts pivotally held together, on one of which is mounted the bed 12 and carriage 13, so that the carriage and bed together with the propelling mechanism and platen may be folded over into compact relation to the machine frame, as shown in dotted lines in Fig. 1. 105

The parts thus far described may be of the usual or of any preferred construction.

To back space the carriage and to move the same against the action of the propelling means, I provide a lever or bar-like element 28, one end of which, as 29, is provided with a tooth or dog which is adapted to engage the teeth of the rack 19. The lever 28 is slotted, as at 30, and passing through said slot is a screw 31 which serves as a pivot for the lever 28 and permits lengthwise movement thereof. The lever 28 is located above the bed 12 and is normally forced in one direction by a spring 32, and at the other end of said lever is a head 33 which is adapted to be engaged by the upturned end 34 of a manually operated lever 35. This lever 35 is pivoted at 36 to one of the parts of the foldable support 11, and on the outer end of the lever is a thumb or finger portion or key 37 by which the lever may be readily moved on its pivot 36. The lever 35 has its inner end under the bed 12 and has its upturned end 34 extending through a slot 38 in the carriage bed, and said end 34 is adapted to engage an inclined portion 39 of the lever 28.

The lever 35 has its part or key 37 within convenient reach of the operator and when moved, the end 34 will engage the head 33 of the lever 28 and will cause the same to move outward, and owing to the inclined or cam part 39, the end or tooth 18 will be caused to engage the rack 19 which will move the rack and the carriage a distance of one space at each movement of the lever 24.

It is to be understood that the invention is not limited to the particular form of back-spacing mechanism as this may be changed so long as it is applied to a foldable or compact typewriter or is within the scope of the claims.

While I show and describe certain parts of a typewriting machine, those parts not claimed herein are claimed in other and pending applications filed by me.

From the foregoing, it will be seen that a simple and efficient back-spacing mechanism is provided for typewriting machines; that said mechanism may be shifted with the platen and the carriage into compact relation to another part of the typewriting machine whether the said shifting movement is over the keyboard or some other part of the machine; that said mechanism is within convenient reach of the operator; and that said mechanism may be readily made and applied as a part of typewriting machines of various constructions.

Having thus described my invention, I claim as new and desire to secure by Letters Patent:

1. In a typewriting machine of the folding type, the combination of a machine frame, a carriage bed, pivotal means for per-

mitting said carriage bed to be folded to abnormal position, a carriage feeding rack, a back-spacing dog carrier, a dog on said carrier adapted to engage the rack, and operative means for the dog carrier carried by 70 the said pivotal means of the carriage bed.

2. In a typewriting machine of the folding type, the combination of a machine frame, a carriage bed, pivotal means for permitting said carriage bed to be folded to 75 abnormal position, a carriage feeding rack, a back-spacing dog carrier mounted on said carriage bed, a dog on said carrier, and a lever mounted on said pivotal means for the carriage bed and operatively connected 80 to move the dog carrier.

3. In a typewriting machine, the combination of a plurality of key-levers, a support, a carriage mounted upon said support and foldable into compact relation to another 85 part of the machine, a rack movable with the carriage, a reciprocating back-spacing dog carrier mounted on the carriage bed, a dog on said carrier and reciprocating therewith, and means adapted to operate the dog 90 carrier and movable with the carriage into its folded position.

4. In a typewriting machine, the combination of a plurality of key-levers, a support, a carriage mounted upon said support and foldable forward into compact relation 95 to the key-levers, a rack movable with the carriage, a dog carrier having a dog to move the rack, and means operative from the front of the machine and adapted to operate the dog carrier and movable with the carriage and dog carrier into its folded position.

5. In a typewriting machine, the combination of a support, arms pivotally held to said support, a carriage mounted upon the arms and movable into compact relation to another part of the machine when not in use, a dog carrier having a dog, means adapted to be engaged by said dog to move the carriage in a direction opposite its letter-spacing movement, and means pivotally held to one of said arms adapted to operate said dog carrier and foldable with the carriage in its compact movement.

6. In a typewriting machine, the combination of a support, a carriage mounted upon the support and foldable into compact relation to another part of the machine when not in use, a dog carrier having a dog and mounted on said carriage support, means adapted to be engaged by said dog and adapted to move the carriage in a direction opposite its letter-spacing movement, and means connected to operate said dog carrier and foldable with the carriage in its compact movement.

7. In a typewriting machine, the combination of a platen carriage, a movable bed for said carriage, a back-spacing dog car-

rier having a dog and mounted on said bed, means adapted to be engaged by said dog and adapted to move the carriage in a direction opposite its letter-spacing movement, 5 a spring for forcing the carrier in one direction, and means movable with the bed and having a loose connection with the dog carrier adapted to operate said carrier.

8. In a typewriting machine, the combination of a support, a carriage feeding rack, a carriage bed pivotally mounted to swing on the support, a dog carrier mounted for reciprocal movement on said carriage bed, a dog mounted upon the dog carrier, 15 means for causing the dog to engage said carriage feed rack when said dog carrier is moved in a direction opposite to that which the carriage rack travels under the influence of the carriage moving power, and 20 means for operating said dog carrier, said dog carrier being capable of movement independent of said operating means.

9. In a typewriting machine, the combination of a carriage feeding rack, a movable carriage bed, a back-spacing dog carrier having a dog and mounted on said bed, a finger key, and means operatively connecting said finger key with said dog carrier, the construction and arrangement of parts 25 being such that said dog carrier may move with the carriage bed independent of said finger key.

10. In a typewriting machine of the foldable type wherein the carriage bed is adapted to be moved to abnormal position, the combination of a support, a carriage bed, a back spacing dog mounted on said carriage bed, a finger key mounted for movement on 30 said support, and operative means connecting said finger key with said back spacing dog.

11. In a typewriting machine of the foldable type wherein the carriage bed is adapted to be moved to an abnormal position, the combination of a back spacing dog, a dog carrier, means for causing said back spacing dog to become operative when said dog carrier is moved, pivotal means about which 45 said carriage is moved to abnormal position, a finger key, and means for operatively connecting said finger key with said dog carrier at all times.

12. In a typewriting machine of the foldable type wherein the carriage bed is adapted to be moved from normal to abnormal position, the combination of a support, a carriage bed, means for permitting said carriage bed to be moved to abnormal position, a dog carrier mounted on the carriage 55 bed and having a back spacing dog, a finger key, and means operatively connecting said finger key with said dog carrier.

13. In a typewriting machine, the combination with a support, of a carriage, a 60 rack, a lever pivotally held under the car-

riage and having a tooth adapted to engage the rack, a spring normally forcing the lever in one direction, means for pivotally holding the lever and permitting it to have a lengthwise movement, said lever having a 70 head with an inclined or cam-like portion, a manually operated lever pivotally held to the support and having an end adapted to engage the head of the first-mentioned lever, and means whereby the operating 75 lever may be moved on its pivot.

14. In a typewriting machine, the combination with a support, of a carriage, a member, a lever pivotally held under the carriage and having a tooth adapted to engage the member, a spring normally forcing the lever in one direction, means for pivotally holding the lever and permitting it to have a lengthwise movement lengthwise of the carriage and under the same, and a 80 manually operated lever pivotally held to the support at substantially right angles to the first-mentioned lever and having an end adapted to engage the head of said first-mentioned lever and having a finger portion 85 located within convenient reach of the operator.

15. In a typewriting machine, the combination of a carriage having a base plate, a carriage bed located under the base plate 90 and along which the carriage is adapted to travel, a rack mounted on the carriage, a longitudinally movable element located between the carriage bed and said base plate and having means to engage the rack and 100 move the carriage for back spacing, means for operating said element, and means to adapt the carriage, bed and element to be moved into substantially overhanging relation to a keyboard to make the machine more 105 compact than when in use.

16. In a typewriting machine, the combination of a carriage having a base plate, a carriage bed located under the base plate and along which the carriage is adapted to 110 travel, a rack mounted on the carriage, a longitudinally movable element located between the carriage bed and said base plate and having means to engage the rack and move the carriage for back spacing, and 115 means for operating said element.

17. In a typewriting machine, the combination of a carriage, a carriage bed along which the carriage is adapted to travel, a longitudinally movable bar-like element pivotally held to move lengthwise of the carriage bed and having means to engage a part movable with the carriage to move the latter for back spacing, and a lever having a loose connection with the bar-like element 120 and adapted to operate said element.

18. In a typewriting machine, the combination of a carriage, a carriage bed along which the carriage is adapted to travel, a 125 rack movable with the carriage, a longitu-

dinally movable bar-like element pivotally held to move lengthwise of the carriage bed and having a tooth movable therewith to engage the rack and move the carriage for 5 back spacing, and a pivotally held lever having a loose connection with the bar-like element and adapted to operate said element.

19. In a typewriting machine, the combination of a carriage, a carriage bed along 10 which the carriage is adapted to travel, a longitudinally movable and pivotally held bar-like element located to have a limited movement lengthwise of the carriage and having means to engage a part movable with 15 the carriage to move the latter for back spacing, said element having a hooked end with a cam portion, and a pivoted lever having one end projecting through the bed and adapted to engage the cam portion of 20 the bar-like element and its other end ex-

tending forward and provided with means to operate said lever.

20. In a typewriting machine, the combination of a carriage, a carriage bed along which the carriage is adapted to travel, a 25 horizontally movable bar-like element located to move lengthwise of the carriage along the upper surface of the bed and under the carriage and having means to engage a part movable with the carriage to 30 move the latter for back spacing, and a horizontally movable and pivoted lever adapted to operate said bar-like element.

This specification signed and witnessed this 2nd day of March, A. D. 1911.

OTTO PETERMANN.
